UNITED STATES PATENT OFFICE.

JOHN KATHE, OF QUINCY, ILLINOIS.

GAS-ENGINE GOVERNOR.

1,351,660.

Specification of Letters Patent. Patented Aug. 31, 1920.

Application filed May 20, 1919. Serial No. 298,557.

To all whom it may concern:

Be it known that I, JOHN KATHE, a citizen of the United States, residing at Quincy, in the county of Adams and State of Illinois, have invented new and useful Improvements in Gas-Engine Governors, of which the following is a specification.

This invention relates to governors particularly designed for use in conjunction with the butter-fly or throttle valves of internal combustion engines.

The object of the invention is to produce a simple, compact and effective governor for the purpose above specified, said governor being adapted to be mounted upon and actuated by any rotating shaft or element of the engine and connected with the throttle valve for actuating the latter in such manner as to prevent the racing of the engine when relieved suddenly from its load, either in whole or in part.

A further object of the invention is to so construct the governor that it may be readily applied to engines already in use in any easy and expeditious manner.

With the above and other objects in view, the invention consists in the novel construction, combination and arrangement of parts herein fully described, illustrated and claimed.

In the accompanying drawings:—

Figure 1 is an enlarged diametrical section through the governor.

Fig. 2 is a plan view of the rotary engine driven member of the governor.

Fig. 3 is a vertical longitudinal section through the rotary member, shown in separation from the engine, and illustrating the associated movable centrifugal control members and plunger.

Fig. 4 is a detail view of one of the centrifugally controlled members.

Fig. 5 is a plan view of the same.

Fig. 6 is a detail view of the plunger guide.

Fig. 7 is an end view of the same.

Fig. 8 is an inner end view of the plunger.

The governor which is particularly designed for use upon internal combustion engines, gas engines and the like, comprises in the preferred embodiment thereof an engine driven rotary member 1 which is preferably of disk shaped formation as illustrated in Figs. 2 and 3. The member 1 is preferably mounted upon a rotary shaft 2 of the engine as shown in Fig. 1 and em-

bodies a plunger 3 the motion of which is imparted to a throttle valve operating rod 4 by means, for example, of a lever 5 fulcrumed at 6 on an arm or bracket 7 projecting from the engine frame as shown in Fig. 1; the said rod 4 being designed to be connected with the operating arm of a throttle valve (not shown). The plunger 3 is mounted for endwise movement in a guide 12 which is shown in the form of a tubular post secured at one end by means of fasteners 13 such as screws to the member 1. The guide 12 therefore has a fixed relation to the center of the rotary member 1. The lower arm of the lever 5 is opposed to the plunger 3, and said plunger 3 is yieldingly pressed in an inward direction or toward the member 1 by means of a compression spring 14 which is interposed between the lower arm 70 of the lever 5 and a speed regulating screw 15 threaded in a housing 16 inclosing the governor mechanism all as shown in Fig. 1. The spring 14 is socketed in and held against lateral deflection by the lever 5 and screw 15. The plunger is provided at its inner end with inclined cam faces 17 as best shown in Fig. 8. The cam faces 17 co-operate with cam portions 18 on opposite radially-movable centrifugal members 19, 85 Figs. 1 to 5. On the inward movements of said members 19, their cam portions operate to move the plunger 3 endwise toward the right in Figs. 1 and 3, against the action of the spring 14. Incidental to the outward 90 movement of the members 19, the spring 14 serves through the lever 5 to press the plunger 3 endwise toward the left in Figs. 1 and 3.

Each of the members 19 is guided in its 95 back and forth movement by a plurality of anti-friction rollers 20 through which are inserted headed and shouldered screws 21 threaded in the inner side of the respective member 19 as shown in Fig. 3. The rotary member 1 is provided with radially elongated slots or guideways 22 in which the rollers 20 operate. In this way the centrifugally controlled members 19 are held in a certain relation to the rotary member 1. 105 Each member 19 is provided with a plurality of raised surfaces or projections 23 on the inner side thereof for the purpose of reducing friction between the member 19 and the rotary member 19. The oppositely 110 located members 19 are formed with inwardly extending and overlapping guiding

tongues 24 which are slidable through an opening in the guide 12, such opening, indicated at 25, being of sufficient width to receive the inner lapped end portions of the 5 oppositely located centrifugally controlled members 19.

As shown in Fig. 3, the oppositely located members 19 are yieldingly pressed toward each other by means of one or more contractile 10 springs 26 attached at opposite ends to a pair of pins 27 inserted through the respective members 19. The springs 26 yield under centrifugal action to permit the members 19 to move outward in a radial path.

15 In view of the foregoing description taken in connection with the accompanying drawings, it will now be seen that as the speed of rotation of the engine shaft increases the speed of the member 1 also increases and the 20 centrifugally controlled members 19 start to move outwardly toward the periphery of the member 1. As members 19 move out the spring 14 moves the plunger 3 inwardly, and incident thereto the speed of the engine is 25 automatically prevented from racing. As the speed reduces, the reverse operation takes effect and the members 19 permit the plunger 3 to move in the opposite direction thereby moving the throttle valve 9 again 30 toward an open position.

The speed regulating screw 15 is threaded through an opening in the housing 16 as shown in Fig. 1. The inner end of the screw 15 is formed with a recess 30 to receive one 35 end of a spring 14 while the opposite extremity of said spring is received in a recess 31 in the adjacent end of the lever 5. Therefore by adjusting the screw 15, the spring 14 may be placed under greater or 40 less tension for regulating the resistance to the movement of the plunger 3. The spring 14 serves to keep the end of the lever 5 snugly against the plunger 3, causing said lever to swing easily upon the inward or 45 return movement of the plunger 3, the lever 5 thereby immediately controlling the con-

nexion 4 which controls the throttle valve of the carburetor in the manner illustrated in the drawings. The housing 16 incloses the governor mechanism and protects the 50 same against dirt, dust and other foreign matter. The speed screw provides for a wide variation in the speed of the engine and enables the speed of the engine to be 55 regulated at the will of the operator without requiring the engine to stop for that purpose.

The governor hereinabove described is simple in construction, reliable in operation and exceedingly compact and will be found 60 a valuable adjunct to a motor vehicle, as it prevents racing of the engine and the injury incident thereto while at the same time saving materially in the amount of gasoline or other fluid fuel used in the operation of the 65 engine. This is particularly true in the case of inexperienced operators of motor vehicles who by improper throttling of the engine waste considerable gasoline, cause the engine to overheat and also cause a rapid accumulation of carbon in the combustion chamber and valve chambers of the engine. 70

I claim:—

The combination in a governor, of a 75 radially-slotted disk-like motor-driven rotary member, a housing in which said member is disposed, centrifugal members held to the face of the rotary member by means movable in the slots of the latter and yieldingly held against outward movement, said 80 centrifugal members having inner lapped cam portions, a tubular guide carried by the motor-driven member and in which said cam portions are movable, a central endwise-movable plunger in said guide and having 85 a cam portion opposed to the cam-portions of the centrifugal members, a lever mounted in the housing and movable by said plunger, and a spring arranged at the opposite side of the lever to the plunger. 90

In testimony whereof I affix my signature.
JOHN KATHE.
